US0D1052552S

(12) **United States Design Patent** (10) **Patent No.:** **US D1,052,552 S**
(45) **Date of Patent:** **** Nov. 26, 2024**

(54) **PORTABLE TELEVISION RECEIVER**

(71) Applicant: **LG ELECTRONICS INC.**, Seoul (KR)

(72) Inventors: **Sangho Lee**, Seoul (KR); **Seala Park**, Seoul (KR)

(73) Assignee: **LG ELECTRONICS INC.**, Seoul (KR)

(**) Term: **15 Years**

(21) Appl. No.: **35/519,156**

(22) Filed: **Nov. 25, 2022**

(80) **Hague Agreement Data**

Int. Filing Date: **Nov. 25, 2022**

Int. Reg. No.: **DM/225908**

Int. Reg. Date: **Nov. 25, 2022**

Int. Reg. Pub. Date: **Dec. 1, 2023**

(30) **Foreign Application Priority Data**

Jul. 28, 2022 (KR) 30-2022-0030531

(51) **LOC (14) Cl.** **14-03**

(57) **CLAIM**

The ornamental design for a portable television receiver as shown and described.

DESCRIPTION

1.1 : Front perspective

1.2 : Back perspective

1.3 : Front

1.4 : Back

1.5 : Left

1.6 : Top

1.7 : Bottom

The claimed design is a portable television receiver equipped with a transparent OLED display; a right view is omitted because it is a mirror image of the left view; the diagonal shading lines are used to show the transparent OLED display and thin lines are drawn therethrough; the

(Continued)

shading lines are used to show the surface of the claimed design and do not represent its surface ornamentation.
